UNITED STATES PATENT OFFICE.

ALFRED W. HOFFMAN, OF NEW YORK, N. Y.

TABULAR CALCULATOR.

1,139,287.

Specification of Letters Patent.

Patented May 11, 1915.

Application filed July 8, 1914. Serial No. 849,708.

To all whom it may concern:

Be it known that I, ALFRED W. HOFFMAN, a citizen of the United States, and a resident of the city of New York, borough of the Bronx, in the county of Bronx and State of New York, have invented a new and Improved Tabular Calculator, of which the following is a full, clear, and exact description.

10 Among the principal objects which the present invention has in view are: to provide an apparatus arranged to readily and quickly furnish mathematical results; to provide tabulating units arranged to provide mathematical results having grouped relation; to provide for amplifying the information relative to any particular unit of the system or element of the apparatus therefor; to provide means for grouping 20 the tabulating members and the record thereon; and to provide means for arranging the tabulating units or members of each group in registered relation to other groups.

25 *Drawings.*—Figure 1 is a perspective view of a corner fragment of an apparatus constructed and arranged to receive tabulating members in accordance with the present invention; Fig. 2 is a detail view on an enlarged scale, showing a fragment of a holding case and tab racks mounted therein, said tab racks and case being constructed in accordance with the present invention; Fig. 3 is a detail view in perspective, showing a modified form of a tab and filler therefor; 35 Fig. 4 is a detail view showing in perspective a further modified form of tab and filler. Fig. 5 is a side view of a tabulating apparatus constructed and arranged in accordance with a modified form; Fig. 6 is a 40 perspective view showing a fragment of the same.

45 *Description.*—In the drawings I have shown an apparatus and tabs therefor constructed and arranged for employment in a system adapted for use where the results of mensuration of yardage and price may be quickly and readily ascertained. It will be understood that the system is equally applicable to other systems of mensuration 50 than that herein described. Though the systems of mensuration herein referred to are those involving multiplication, it will be understood that the invention has within its scope systems of mensuration wherein division, addition, or subtraction are em-

ployed. In each of the systems, two factors are known; to wit, a quantity and a power by which the quantity is to be increased or diminished. Also, the quantity referred to is preferably expressed as a whole accompanied by fractional divisions thereof.

60 The system is embodied in the present invention in a case or box 9. The box 9 is provided with a cover 10. Said cover is cut away to form an opening 11, through which 65 may be seen the tops of racks 12. Surrounding the opening 11, the margins 13 and 14 have scales or information printed thereon. Thus, on the margin 13 the words "Yards and eighths" indicate that the 70 table adjacent the words has relation to yards and eighths of yards. The words "Dollars and cents" on the margin 14 indicate that the adjacent table is to be read as dollars and fractions of dollars.

75 The various racks 12 are preferably trapezoidal tubes, the shape being provided to incline backward the tabbed holders 15. The holders 15, as shown best in Fig. 3 of the drawings, have overturned edges 16 spaced 80 from the body of the holders to form lengthwise grooves 29, wherein fillers or cards may be placed.

85 The racks 12 are suitably perforated or pierced to hold, in sliding and guided relation the holders 15. To hold the various racks, rails 17 are mounted on the sides of the box 9 as best shown in Fig. 2 of the drawings, whereon the ends of said racks rest when in service. As shown in Fig. 2, 90 the racks 12 are nested or packed within the box 9 in a manner to form mutual supports each for the other. The perforations with which the racks 12 are provided are staggered, as seen best in Fig. 1 of the drawings, 95 to permit the tab heads 18 with which each holder is provided, to be viewed easily, while economizing as much as possible the space occupied by the aggregated holders 15 within the box 9. In their recumbent or 100 depressed position, the holders 15 are supported by the heads 18, which recline on the top of the several racks overhanging the ends of the perforations or slots with which said racks are provided. The heads 18 are 105 used, in service, for raising the holders 15, as shown best in Fig. 2 of the drawings. In the raised position, the holders naturally incline backward, and, if unrestrained, place shoulders 19 formed at the lower ends 110

of the edges 16, over the bottoms of the racks 12. The holders 15 are held in the upright position in this way until lifted forward to remove said shoulders from engagement with the bottoms of said racks. When drawing the holders 15 to their outermost position, they are restrained or prevented from being drawn out of engagement with the racks 12 by hooked ends 20, 10 with which each of the holders 15 is provided. These ends engage the under sides of the various racks, and arrest the holders in the fully-extended position. In this position, the operator presses gently backward 15 the holders 15, and thereby causes the shoulders 19 of the edges 16 to engage the bottoms of the racks 12, in the manner as shown in the drawings.

Each of the holders 15 is supplied with a 20 filler or card 21. Each filler 21, as shown best in Fig. 1 of the drawings, has imprinted thereon, adjacent one of its elongated margins, a table indicating in serial order a characteristic or key number, such as "5," as shown by the raised holder in said Fig. 1 of the drawings. Succeeding the key number in the series are the fractions to be added to the key number, and for which, on the opposite margin of the 30 filler, the results of the mensuration are given. These results will constantly vary in accordance with the relation to which the particular tab and filler used, bears to the tables on the margins 13 and 14. The key number referred to is imprinted on each of the tab heads 18, and each key number is common or universal to all of the holders of a certain series thus designated. In the drawings, these key numbers are shown as related to a corresponding key number 35 marked on the margin 13. In the examples emphasized in the drawings, and as above stated, the key number is "5," and it will be noted that on the margin on the block or 40 space designated by the numeral "22," the key number is "5," and that in line therewith, extending to the limit of the figure, and to the right thereof, each of the tab heads 18 is so marked. Thus, it will be understood that each of the holders 15 having the mark "5" at the upper end thereof and 45 in line with the block 22, will have a filler 21 having at the upper end thereof the numeral "5," and serially disposed below the same, the fractions to be added thereto. Said key number and the fractions in each of the fillers will be the same. On the opposite margin, however, the results in each of the fillers will vary, as will also vary the 50 numerals with which the heads 18 are provided, said numerals being placed below the key number, and referring to, to be identified with, the vertical columns which are indicated on the margin 14 by the figures beginning with ".0-1/2" and ending with ".5-1/2."

While the example illustrated in the drawings is limited to ".40," it will be understood that these columns may be extended to suit the current conditions of the business to which the system is applied.

In each filler, the lower number is used as a multiplier for the key number and for each of the fractions placed on said filler. In the example shown in Fig. 1 of the drawings, it will be seen that the key number of the holder 15, which is shown in its raised position, is ".5." The column number is ".08." The first example on the filler 21 is that of "5," the key number, multiplied by .08, giving the result adjacent the right-hand edge of the filler as ".40." The succeeding number under the key number "5" is ".1/8." Opposite this will be found ".41," which is the multiplication of 5-1/8 by .08, and so on down the two columns, on the one side the numbers being gradually increased by a constant power, and the numbers in the opposite column being the result of the multiplication of the numbers in the first column by the lower number on the tab head 18 of the holder 15.

In Fig. 3 of the drawings, a modified form of the filler is shown, the modification consisting in substituting for the usual card a folder, such as 23. The folder is preferably made of thin paper, the object being to increase the surface upon which information or data may be inscribed. Adjacent the lower end of the holders 15, a small bench 24 forms a stop or support for the filler.

In the modified form shown in Fig. 4, the tab head 25 is set back and connected with the body of the holder 15 by an intermediate bench portion 26. The object of the construction is to permit the employment of a removable index card 27, which is held on the tab head 25 by means of the overturned edges 28, arranged substantially as shown. When employing tab holders such as shown in Fig. 4 of the drawings, the key number and column number above referred to, may be inscribed on cards, such as 27. This arrangement provides for altering at any time the system for which the holders and receptacle are provided.

Operation.—When operating with an apparatus equipped as shown in the drawings, and as above described, the operation is as follows: If the transaction be a sale of 5-5/8 yards of material, the price of which is eight cents per yard, the operator follows down the column marked ".08" until he comes to the tab head having the key number "5." He now lifts the tabbed holder until the shoulders 19 engage and rest on the lower wall of the rack 12 in which it is mounted. By referring to the column at the left on the filler 21, he sees that opposite the "5/8" is the price ".45," which is the result he has been looking for, or the price of 5-5/8 yards

of material at eight cents per yard. Having ascertained the result, by pressing the tab head 18 slightly forward, the holder 15 is moved to alinement with the slot in the 5 jack, and drops to the normal position shown best in Fig. 2 of the drawings.

As indicated, the number of uses, and the scope of the apparatus may be widely varied, it being possible by the employment 10 of this apparatus to provide any number of mathematical results, and a rapid and simple index thereto. Also, by means of the coordinate columns, it is possible to employ the apparatus for information of various 15 kinds, said information being contained in condensed form.

In the modified form of the apparatus shown in Figs. 5 and 6, the inclined arrangement of the face of the box and of the 20 holders 15 therein enables the various tabs 25 to be constantly in view.

Claims:

1. An apparatus as characterized, comprising a plurality of racks, each having a 25 perforated upper and lower wall; and a plurality of elongated tabbed holders, each having a shoulder at the lower end thereof to rest upon the lower wall of said racks to support said holders in raised position, and 30 a tab head resting on the upper wall of said racks to support said holders in the lower position thereof.

2. An apparatus as characterized, comprising a plurality of racks, each having a 35 perforated upper and lower wall; a plurality of elongated tabbed holders, each having a shoulder at the lower end thereof to rest upon the lower wall of said racks to support said holders in raised position, and 40 a tab head resting on the upper wall of said racks to support said holders in the lower position thereof; and means mounted on said holders for preventing lifting the same out of said racks.

45 3. An apparatus as characterized, comprising a plurality of racks, each having a perforated upper and lower wall; a plurality of elongated tabbed holders, each having a shoulder at the lower end thereof to rest upon the lower wall of said racks to support said holders in raised position, and 50 a tab head resting on the upper wall of said racks to support said holders in the lower position thereof; and hooked ends, one 55 formed on each of said holders for engaging

the under side of said racks when said holders are lifted to exposed position.

4. An apparatus as characterized, comprising a plurality of racks, each having a perforated upper and lower wall; a plurality of elongated tabbed holders, each having a shoulder at the lower end thereof to rest upon the lower wall of said racks to support said holders in raised position, and a tab head resting on the upper wall of said 60 racks to support said holders in the lower position thereof; and a plurality of flanges, oppositely disposed and fixedly connected with each of said holders to form channels for holding a filler. 70

5. An apparatus as characterized, comprising a plurality of racks, each having a perforated upper and lower wall; a plurality of elongated tabbed holders, each having a shoulder at the lower end thereof to 75 rest upon the lower wall of said racks to support said holders in raised position, and a tab head resting on the upper wall of said racks to support said holders in the lower position thereof; a plurality of flanges oppositely disposed and fixedly connected with 80 each of said holders to form channels for holding a filler; and a bracket bench mounted on said holder within said channels to form a rest for said filler. 85

6. An apparatus as characterized, comprising a plurality of racks, each having a perforated upper and lower wall; a plurality of elongated tabbed holders, each having a shoulder at the lower end thereof to 90 rest upon the lower wall of said racks to support said holders in raised position, and a tab head resting on the upper wall of said racks to support said holders in the lower position thereof; a plurality of flanges, oppositely disposed and fixedly connected with 95 each of said holders to form channels for holding a filler; a removable filler adapted for insertion within said channels; a bracket bench mounted on said holders within said 100 channels to form a rest for said filler; and means provided on said tabbed heads for indexing the same.

In testimony whereof I have signed my name to this specification in the presence of 105 two subscribing witnesses.

ALFRED W. HOFFMAN.
